A. HORMEL

WASHING MACHINE

Filed Jan. 14, 1924

INVENTOR

AUGUST HORMEL

BY

Julian H. Hormel
ATTORNEY

UNITED STATES PATENT OFFICE.

AUGUST HORMEL, OF JERSEY CITY, NEW JERSEY.

WASHING MACHINE.

Application filed January 14, 1924. Serial No. 686,033.

To all whom it may concern:

Be it known that I, AUGUST HORMEL, a citizen of the United States, and a resident of Jersey City, county of Hudson, and State of New Jersey, have invented certain new and useful Improvements in Washing Machines, of which the following is a specification.

This invention relates to improvements in washing machines.

One of the objects of my invention is to produce a washing machine by the use of which the rubbing operation in washing clothes is relieved from a reciprocating motion on a stationary rubbing element to a mere pressing or holding of the clothes in contact with a rotating or revolving rubbing surface, preferably comprising a rotating disc having radial corrugations, thus greatly reducing the manual energy necessarily employed in the said rubbing operation.

Another object of my invention is the production of a washing machine which will embody a substantially flat frame or rubbing board having mounted thereon a rotating rubbing-element and a self-contained power-unit for rotating the rubbing element also mounted on said board so as to produce a self-contained and compact unitary structure.

Another object of my invention is to produce a washing machine of the type specified of extremely simple construction which may be manufactured and sold at a low cost and which is durable and not likely to get out of order.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a plan view of a power actuated washing machine embodying my invention;

Fig. 2 is a longitudinal section on the line 2—2 of Fig. 1;

Fig. 3 is a transverse section on the line 3—3 of Fig. 1; and

Fig. 4 is a plan view of my bearing frame with the rubbing element removed.

Referring now to these drawings, which

illustrate a preferred embodiment of my invention, 1 indicates a washing machine which, in the embodiment shown, comprises an elongated flat frame or board intended to be supported in a wash-tub in the usual inclined position and having side rails or stiles 2—2^a connected together at the top end by a transverse member 3. The lower ends of the stiles form legs 2^b—2^c for the frame or board and in the embodiment shown the transverse member 3 is provided with a depressed soap retaining groove 4 and a clothes-guiding surface 5, which in the embodiment shown is flat and uncorrugated. Suitably mounted between the frame members or stiles 2—2^a intermediate the ends thereof and having its top surface substantially flush with the surface of clothes-guiding surface 5 is a rotatable rubbing element comprising a flat disc 6 having a roughened or corrugated rubbing surface 7 and, as shown, having corrugations 7^a extending radially of the disc. This rotatable rubbing element is preferably mounted in a depression below the upper surface of the board so that the corrugated rubbing surface 7 will, as aforesaid, be substantially flush with the guiding surface 5.

In the embodiment shown, the rubbing disc 6 has a bearing bore 6^a which fits over a bearing pin 8 rotatably supported in a bearing 9 formed integrally in a bearing-box 10 provided with a depressed mounting chamber 10^a having annular walls 11 closely surrounding the disc 6 and also having a marginal flange 12 extending completely around the rubbing element, and preferably having its top surface substantially flush and abutting with the guiding surface 5. In the said preferred embodiment shown, I locate within the mounting box 10 a gear preferably comprising a worm-gear for rotating the rubbing disc or plate 6. This gear comprises a worm-wheel 13 coaxial with the disc and, as shown, mounted on an intermediate portion 8^a of the pin 8. The pin 8 is also preferably provided with a separating plate 8^b extending between the bottom surface 6^b of the disc and the upper surface 13^a of the worm wheel. The disc is preferably detachably fastened to the worm wheel and bearing pin through said separator plate by screws 14. In the said preferred embodiment shown the disc is also preferably provided adjacent to its perim-

eter with an annular bearing track 6^c which bears against rollers 15 mounted on the wall 11 of the bearing box 10. Said disc 6 also has a perimetral flange 6^d extending radially 5 beyond the annular track 6^c. This flange 6^d extends over the L-shaped edge 11^a of the depressed mounting chamber 10^a. The worm-wheel 13 meshes with a worm 13^a on a longitudinally-extending shaft 16 mounted, 10 as shown, in bearing brackets 17 in the mounting box 10. The shaft 16 may be rotated in any suitable manner or by any suitable power device, and as shown the said shaft 16 is connected to an electric motor 18 located at the upper end of the board between the soap depression 4 and the downwardly bent top edge or rail 1^a of the said frame or board.

20 The motor is driven from any suitable source of power not shown.

In operation, the clothes to be rubbed are manually or in any other suitable manner held or pressed in contact with the rubbing surface of the rotating element which is 25 continuously rotated by the motor. Obviously the surface of the clothes which is pressed against the rotating corrugations will be rubbed by such corrugations and the usual hard manual labor incident to reciprocating the clothes on the ordinary stationary rubbing surface of a wash-board 30 is eliminated.

Having described my invention, I claim:—

35 1. A washing machine embodying a substantially flat frame having a depressed

mounting chamber between the ends of said frame, a substantially flat rotatable rubbing element supported in said mounting chamber comprising a disc having a rubbing surface, and means for rotating said element 40 to enable the rubbing of clothes held in contact therewith.

2. A washing machine embodying a substantially flat frame having a depressed mounting chamber between the ends of said frame, a substantially flat rotatable rubbing element supported in said mounting chamber comprising a disc having a rubbing surface, a worm gear for rotating said disc and an electric motor mounted on the said frame 45 50 for operating said worm gear to rotate the rubbing element.

3. A washing machine embodying a substantially flat frame having a depressed mounting chamber between the ends of said frame, a substantially flat rotatable rubbing element supported in said mounting chamber comprising a disc having a rubbing surface, a worm mounted within said depressed chamber coaxially with said disc, a worm and worm shaft for rotating said worm wheel and an electric motor also mounted on 55 60 said frame.

In witness whereof, I have signed my name to the foregoing specification in the presence of two subscribing witnesses.

AUGUST HORMEL.
